UNITED STATES PATENT OFFICE.

JOHN E. VAIL AND CHARLES E. STUBER, OF GARDEN GROVE, IOWA.

CLOTHES-WASHING DEVICE.

Application filed April 17, 1923. Serial No. 632,804.

To all whom it may concern:

Be it known that we, JOHN E. VAIL and CHARLES E. STUBER, citizens of the United States, and residents of Garden Grove, in the county of Decatur and State of Iowa, have invented a new and Improved Clothes-Washing Device, of which the following is a description.

Our invention relates to a device in the form of a waterproof bag within which clothes may be placed and the sides of the bag manipulated to effect a washing of the clothes.

The general object of our invention is to provide a washing device particularly useful for washing babies' clothes and other small and light garments or other articles, and especially adapted to be carried by travelers and tourists including those touring by automobile, railways or steamships.

A more specific object of the invention is to provide a washing device in the form of a bag in which the articles to be washed may be placed and which is useful as a water bucket convenient for example in filling the radiator of an automobile.

The nature of the invention and its distinguishing features and advantages will clearly appear as the description proceeds.

Reference is to be had to the accompanying drawings forming a part of this specification, it being understood that the drawings are merely illustrative of one example of the invention.

Figure 1 is a side elevation of a washing device embodying our invention, a portion of the inner side of the device being broken away;

Figure 2 is a transverse section in a plane indicated by the line 2—2, Figure 1;

In carrying out our invention in accordance with the illustrated example a bag is provided having sides 10 and 11, the bag being made with suitable waterproof material and in any desired shape. On the bag at the inner surface of the sides 10 and 11, rubbing ribs 12 are provided advantageously by ribbed strips 13 of rubber vulcanized onto the bag sides.

The ribs 12, it will be observed, are oblique to the vertical axis of the bag and the ribs on one side 10 cross the similar ribs on the opposite side 11. The purpose of giving obliquity to the ribs as shown is to make the rubbing action effective and to give the

clothes a tendency to keep moving toward the center rather than toward the corners of the bag.

On the outer surface of the bag at both sides are hand loops or equivalent hand holds 14 which may be made of strips of broad tape secured by adhesive material, stitched or the like at their ends to the bag. There is a pair of the hand loops 14 on the outer surface of each side so that each hand of the user may be slipped through one or a pair of loops to hold the bag between the hands. With the bag held by the hands through the medium of the loops 14 the sides may be rubbed so that the ribs 12 will effectively cleanse the clothes.

In practice the clothes are placed in the bag with water and soap or other detergent and the bag hung up until the clothes have soaked for the proper period of time. The washing operation is then carried out and afterwards the dirty water is poured away and clean water substituted so that by a further rubbing of the sides of the bag the clothes may be thoroughly rinsed. For suspending the bag during the soaking of the clothes a twisted handle 16 is shown on the bag at the top in the illustrated example, said handle being adapted to be hung on any convenient part of an automobile, on a fence, tree, or the like, or on a fixture in the wash room of a railway train or in the stateroom on a boat or ship.

Advantageously, in practice, we provide the bag within the open top with a flap 15 which when folded into the inner position in the bag lies between the ribs and serves to prevent the splashing of water in the washing of the clothes.

For draining the bag a drain cock 17 is provided at the bottom of the bag, here shown as positioned at the corner. Said drain cock also serves to adapt the bag for use as a water bucket for carrying water for example to an automobile and then filling said radiator by placing the cock 17 at the radiator neck.

We would state in conclusion that while the illustrated example constitutes a practical embodiment of our invention, we do not limit ourselves strictly to the exact details herein illustrated, since, manifestly, the same can be considerably varied without departure from the spirit of the invention as defined in the appended claims.

Having thus described our invention, we claim:—

1. A clothes washing device consisting of a waterproof bag adapted to contain the clothes and washing water, and rubbing ribs on the bag in position to have rubbing contact with the clothes by a relative movement of the sides of the bag.
2. A clothes washing device consisting of a waterproof bag adapted to contain the clothes and washing water, and oblique ribs on the interior of the bag positioned to have rubbing contact with the clothes within the bag when the sides of the bag are manipulated with a rubbing action.
3. A clothes washing device consisting of a waterproof bag adapted to contain the clothes and washing water, and oblique ribs on opposite sides of the interior of the bag, the ribs on the respective sides being of opposite obliquity.
4. A washing device consisting of a waterproof bag adapted to contain clothes and washing water and having members on the

interior thereof adapted to have rubbing contact with the clothes when placed within the bag, and handholds on opposite exterior sides of the bag for manipulating the sides of the bag to effect rubbing action on the clothes.

5. A clothes washing device consisting of a waterproof bag adapted to contain the clothes and washing water, and rubbing ribs on the bag in position to have rubbing contact with the clothes by a relative movement of the sides of the bag; together with a flap within the bag at the top to prevent splashing of the washing water.

6. A clothes washing device consisting of a waterproof bag adapted to contain the clothes and washing water, and rubbing ribs on the bag in position to have rubbing contact with the clothes by a relative movement of the sides of the bag; together with transverse hand loops arranged in alining pairs on the exterior of the bag at opposite sides.

JOHN E. VAIL.

CHARLES E. STUBER.
